Primary Examiner — Dominic Simone(74) Attorney, Agent, or Firm — Morgan, Lewis & Bockius LLP(57) CLAIM

An ornamental design for a single-sole shoe, as shown and described.

DESCRIPTION

FIG. 1 is a perspective view of our new design of a single-sole shoe;

FIG. 2 is a first side view of the design of FIG. 1;

FIG. 3 is a second side view of the design of FIG. 1;

FIG. 4 is a top view of the design of FIG. 1;

FIG. 5 is a bottom view of the design of FIG. 1;

FIG. 6 is a front view of the design of FIG. 1; and,

FIG. 7 is a back view of the design of FIG. 1.

The broken lines illustrating the heel stripe as well as the channel on the sole in the above described Figures are for illustrative purposes only and form no part of the claimed design.
